UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

MEANS FOR SLIDINGLY SUPPORTING FOLDING DOORS.

1,357,299.

Specification of Letters Patent. Patented Nov. 2, 1920.

Application filed April 21, 1919. Serial No. 291,647.

To all whom it may concern:

Be it known that I, ELLIS J. G. PHILLIPS, a citizen of the United States, and a resident of Aurora, in the county of Kane and State of Illinois, have invented certain new and useful Improvements in Means for Slidingly Supporting Folding Doors, of which the following is a specification, reference being had to the accompanying drawings.

This invention relates to improved means for slidingly supporting folding doors, and is an improvement upon the construction shown and described in Letters Patent No. 1,160,198, dated November 16, 1915, granted upon my application. In that patent was described a means for supporting a plurality of door sections hinged together and one of the said sections being hinged to a support such as the side member of a doorway frame. That construction employed an adjustable track movable on a vertical pivot so as to be movable toward and from the doorway, in which track was movable a wheeled carriage that was connected by a swiveling pendent with that door section farthest removed from the section hinged to the fixed support. Such patented construction has proven very satisfactory, but its effectiveness is limited to doorways of less width than is now frequently met with, and it is with the object of furnishing a closure for very wide doorways and at the same time preserving the very desirable feature of having the various door sections or members hinged edge to edge that the present improved construction has been devised.

In carrying out my invention I employ two overhead tracks arranged parallel with each other and supported from adjustable bracket means, in one of which tracks runs a wheeled carriage or hanger suitably connected by a swiveling pendent with one of the intermediate door sections, and in the other of which runs another similar carriage similarly connected with that door section farthest removed from the section that is hinged to the jamb or other fixed support,—all as shown in the drawings and hereinafter fully described. That which I believe to be new will be pointed out in the claims.

In the drawings,—

Figure 1 is an inside view of the upper part of two sets of doors supported from two sets of inclined tracks, each set of said doors as here shown consisting of four sections hinged together and adapted to close one-half of a doorway;

Fig. 2 is an enlarged sectional view through one of the sets of doors, the section being taken at line 2—2 of Fig. 1, and the view showing in dotted lines the doors when in partly-opened position and showing them also in dotted lines in fully-opened position;

Fig. 3 is a perspective view of the upper part of the set of four door sections and their tracks that are shown at the left-hand side of Fig. 1, the view being of the inside faces of the doors as in said Fig. 1, and showing in dotted lines the position of the door sections when moved into fully-opened position;

Fig. 4 is a detail, being a top view of one of the long supporting arms from which the two parallel tracks are adjustably supported;

Fig. 5 is a side elevation of the arm of Fig. 4 and showing in end elevation the means by which the two parallel tracks are adjustably connected with and supported from said arm, the said tracks being in vertical cross-section;

Figs. 6—7 are views similar to Figs. 4—5, respectively, but showing the shorter intermediate supporting arms for the longer track member only;

Fig. 8 is a detail, being an elevation of the door-supporting means that are employed to hold that end of the long track member that comes substantially over the center of the doorway, a portion of the door section and a portion of the building wall over the doorway being also shown; and

Fig. 9 is a detail partly in horizontal section illustrating a slight modification in construction that will permit the doors to be turned farther back so as to be substantially entirely out of the doorway when in completely-opened position.

Referring to the several figures of the drawings, in which corresponding parts are indicated by like reference characters,—10, 11, 12 and 13 indicate four door sections

that are hingedly connected together at their respective abutting edges by hinges 14, such hinges being arranged on opposite sides of the door sections so as to permit a folding of 5 the doors, one upon the other, in the manner clearly indicated by the dotted lines in Fig. 2. The door section 10 is the one at the extreme side of the doorway, and it is secured by hinges, one of which is shown at 15, to 10 the vertical member or jamb 16 of the doorway. The door sections referred to are shown as closing one-half of the doorway, and the other half will be closed by four other similar doors, similar in all respects. 15 These last-named doors and the parts connected therewith are indicated by the same reference characters, with the addition thereto of the letter *a*, and inasmuch as the construction and arrangement of the doors 20 and all of the parts connected or co-acting therewith are the same for one side of the doorway as for the other, the detailed description will be given only in connection with the set of sections numbered from 10 25 to 13, and such set will be found illustrated in Figs. 2 to 9. 17 indicates locking devices of any approved type, mounted on the inner faces of some of the door sections and adapted to cause the projection of locking bolts 30 into upper and lower sockets, as usual. 18—19 indicate two sections of track secured against the face of the building wall in which is the doorway guarded by the doors referred to, such track sections being, 35 of course, located above the plane of the upper edge of the doorway. Each of the track sections may be of any well known construction, and, as shown, each consists of a strip of sheet metal bent to form a top 40 portion, two parallel sides, and inturned lower portions that form rails upon which the wheels of the carriage or hanger run, the pendent depending from each hanger or carriage through the slot between the rails, 45 as usual. In Fig. 8 is shown such a hanger or carriage, the same being indicated by 20, and the pendent that depends therefrom is indicated by 21.

As clearly shown in the drawings, the 50 track member 18 is substantially twice as long as the track member 19, such length of the member 18 being substantially equal to the combined width of the door sections 10—11—12—13, whereas the length of the 55 track member 19 equals substantially the combined width of the two door sections 10—11. These track members are arranged parallel with each other, as best shown in Fig. 2, and they are both so inclined that 60 the ends thereof near the side of the doorway stand at a considerable distance away from the doorway, while their other ends lie close to the wall in which the doorway is formed. For convenience, the ends of the 65 track members near the side of the doorway, and farthest removed therefrom, will be referred to as the outer ends, and the other ends of such members as the inner ends. The track members are supported and held in parallel relation by means of a 70 plurality of devices secured to and extending out from the wall in which the doorway is formed, said devices being best shown in Figs. 4 to 8, inclusive. Referring to these devices, 22 indicates a comparatively long 75 arm extending horizontally over the two track members 18—19, and having a turned end portion 23 adapted to lie against and be secured by bolts to the wall in which the doorway is formed. In the construction 80 shown, two of these arms 22 are employed, one near the outer end of the track members, and one at a point substantially midway between the ends of the short track member 19, as clearly shown in Fig. 3. Each arm 22 85 is adapted to have connected with it means for suspending the two track members, which means, in the construction shown, comprise comparatively long bolts 24—25 that carry, respectively, track brackets 90 26—27 which are shaped to receive and suitably hold the track members 18—19, respectively. Each of the bolts 24—25 passes through one of a series of holes in the arm 22, and by passing these bolts through the 95 desired openings the tracks may be held at any desired distance from the wall. As shown, each bolt 24—25 is provided with a nut above and below the arm, whereby by the adjustment of the nuts the tracks held 100 by such bolts may be secured rigidly in position. 28—29 indicate angular braces bolted to the front wall of the brackets 26—27, respectively, and held against the under face of the arm 22 by the set nuts carried by the 105 bolts 24—25, respectively. Each arm 22 is additionally supported by a rod 30 depending from any suitable overhead support, the rod being screw-threaded at its lower end and passing through an opening in the end 110 of the arm—nuts being screwed upon such end and bearing against the upper and lower faces of said arm, as best shown in Fig. 5. 31 indicates another angular arm secured to the building wall as are the arms 115 22, and extending over the inner end of the short track member 19, and carrying another arm 32, through an opening in which extends a bolt 33, from which support is given to a bracket 34 that is similar to the 120 brackets 26—27, and which supports the central portion of the track member 18, the bolt 33 being secured in place by nuts as are the bolts 24—25. The outer end of the arm is turned down, as at 35, to lie alongside of 125 the outer face of the bracket 34, to which it is bolted. As shown in Fig. 6, the arms 31—32 are adjustable relative to each other by reason of the bolt that secures them together passing through a slot 36. In addition 130

tion to the supporting means just described that extends over the shorter track member and supports the central portion of the long track member, I provide another support of the same construction, as seen in Fig. 3, which is located substantially midway between the inner end of the short track member and the inner end of the long track member. The inner end of each of the track members is supported by means of an angular bracket 37 bolted to the wall of the building, and having bolted to its horizontal portion a track bracket 38,—see Fig. 8, which shows the supporting means for the inner end of the long track member 18.

39 indicates a hanger arm, one being bolted to the face of the door section 11 and one to the face of the door section 13, and the same being secured respectively to the pendants 21 of the hangers or carriages that travel in the respective tracks 18—19, the attachment in each instance being of a character to permit of a swiveling action of the pendent with respect to its connecting member 39.

It will be understood that by properly loosening the nuts on the various bolts, from which the several track brackets are suspended, such brackets can be turned to adapt themselves to the required inclination of the tracks, and thereafter be tightened to hold such brackets and tracks firmly in place. The desired inward and outward adjustment of the track brackets is permitted, of course, by reason of the provision of the holes in the comparatively long brackets 22 and the slots in the bracket members 32, and while I have shown, as stated, the holes in one set of brackets and the slots 36 in the other set of brackets, it will be understood that slots may be employed where holes are now shown, and vice versa.

It is sometimes desirable that the door sections, when folded together, shall be thrown back so as to leave the doorway unobstructed even to the extent of their combined width, and when there is space enough at the side of a doorway to receive the folded-together portions, I contemplate, as a modification of the construction described, extending the inner ends of the track members some little distance beyond the side of the doorway, as shown in Fig. 9. In said figure, the edge of the door opening is indicated by *x*, and it will be noted that the two track members are extended some little distance beyond such point, and the supporting means for such projected ends of the track are arranged correspondingly at one side of the doorway instead of just at the edge of the doorway, as in the other figures. Such arrangement of the parts permits, as will be seen by Fig. 9, the turning of the folded-together doors back so as to be practically wholly out of the doorway and approxi-

mately parallel with the wall in which the doorway is made. As the parts themselves are the same in all respects, except as to length of tracks, as in the other figures, they bear the same reference numerals. 70

By my improved construction I am able to provide means for effectively supporting a large number of door sections that are hinged together, and enabling them to be supported by overhead trolleys so 75 that they may be moved into and out of closed position as effectively as when but two sections were employed, as in my said former construction. This is of very great 80 advantage in view of the fact that in many situations very wide doorways are desired and it is desirable to close the same by sliding doors that when opened will occupy the minimum amount of space. By my improved construction I am able to hang four 85 door sections connected together, and move them as readily to one side of the doorway as was formerly possible with two such door sections, because by the use of the two parallel track members 18—19 the weight of 90 the door sections is divided between such track members, whereas if only a single track member were employed, as in said former construction, the weight of so many door sections of the same size would tend to 95 impose too great a strain upon the hinges that connect the door sections as well as upon the supporting means. It will be seen, therefore, that by the construction herein described I am able to connect up and operate as a single unit the same number and weight of door sections that heretofore has generally had to be divided into two such units. 100

What I claim as my invention and desire 105 to secure by Letters Patent, is:—

1. The combination of two inclined parallel tracks, a series of doors hinged together, a fixed support to which one of said doors is hinged, two hangers 110 movably mounted on said tracks, respectively, and connections between said hangers and two of said doors for movably supporting said series of doors from said tracks.

2. The combination of a series of doors 115 hinged together, a fixed support to which one of the end doors of said series is hinged, a hanger connected to the other one of the end doors of said series, a second hanger connected to an 120 intermediate door of said series, and two tracks upon which said hangers are movably mounted respectively for supporting said series of doors.

3. The combination of two tracks of different lengths, means for pivotally securing one end of each track adjacent to the upper edge of a doorway, said ends being at different distances from one side of the doorway and the other ends being adjacent to 130

said side, adjustable means for holding said tracks parallel with each other and inclined away from the doorway, a series of doors hingedly connected together, and two hangers movably mounted on said tracks, respectively, said hangers being connected to different doors of said series.

4. The combination of a series of doors hingedly connected together, a fixed support to which one of the end doors of said series is hingedly connected, a bracket adjacent to said fixed support, two tracks hav-

ing their end portions mounted on said bracket, a second bracket supporting the opposite end portion of one of said tracks adjacent to the edge of an intermediate door of said series, a third bracket supporting the opposite end portion of the other track adjacent to the edge of another of said doors, and two hangers connected with two of said doors respectively and movable along said tracks for supporting said series of doors. 15 20

ELLIS J. G. PHILLIPS.
